UNITED STATES PATENT OFFICE.

HARRY E. TOWNSEND, OF BROOKLYN, NEW YORK, ASSIGNOR TO THE ANCHOR CAP & CLOSURE CORPORATION, OF BROOKLYN, NEW YORK, A CORPORATION OF NEW YORK.

SEALING-CLOSURE WITH REMOVABLE GASKET.

1,242,742.

Specification of Letters Patent.

Patented Oct. 9, 1917.

Application filed January 10, 1917. Serial No. 141,551.

To all whom it may concern:

Be it known that I, HARRY E. TOWNSEND, a citizen of the United States, and a resident of the city of Brooklyn, in the county of Kings, State of New York, have invented certain new and useful Improvements in Sealing-Closures with Removable Gaskets, of which the following is a specification.

This invention relates to sealing closures 10 adapted to be applied to glass containers and the like and has particular reference to the type of closure disclosed in my prior Patent No. 1,159,624, and in my application for Patent Serial No. 141,552, filed the 15 10th day of January 1917, and constitutes a further development in the art of this type of closures and upon which this invention is an improvement.

The principal object of this invention is 20 to provide a closure wherein the lacquer skin is not destroyed by the sealing operation; wherein the seal is effected with a minimum amount of power; wherein still further variation in sizes of containers is 25 admitted thereby reducing breakage; and also wherein provision is made enabling the seal to be easily and quickly broken whereby the closure may be easily removed.

Other and further objects of the present 30 invention will in part be obvious and will in part be pointed out hereinafter in the specification following by reference to the accompanying drawings wherein like parts are represented by like characters throughout the several views thereof.

Figure 1 illustrates a glass container sealed in accordance with this invention.

Fig. 2 is a detail view illustrating a cross-section through a portion of the sealing dies 40 and the sealing closure prior to the sealing operation.

Fig. 3 is a view similar to Fig. 2 with the exception that the sealing operation is completed.

45 Fig. 4 shows the manner in which the gasket may be removed after the edge has been flattened or pounded as illustrated in Fig. 5.

50 Fig. 5 is a view showing the distortion of the edge due to flattening of the bead by pounding or otherwise.

The closure is adapted to be seated on a glass container 1 which may be provided with a cylindrical sealing wall 2 adjacent 55 the mouth thereof, and said closure prior

to being sealed comprises a top portion 4 which carries an annular bead having an upper wall 5, a side wall 6, and a slightly inturned edge 7. The annular bead preferably is disposed below the top 4 as by means of an annular rim 8 in order to enable the seal to be effected slightly below the upper edge of the glass container since the edges of the container in most cases include more irregularities than the side wall 65 thereof. The annular bead carries a gasket 9 comprising an annular ring of suitable plastic material. The dies for forming the finished closure comprise an anvil die 10 which is provided with an inclined surface 11 and a vertical surface 12 which may be substantially parallel to the side wall of the container. The chuck or upper die 14 may be provided with a vertical supporting wall 15 and an inclined face 16 which may 70 be substantially parallel to the inclined surface 11 on the anvil member. The immediately foregoing descriptive matter refers to the construction prior to the sealing operation.

80 The closure after being sealed comprises substantially an annular skirt 17 which forms the major support for the compressed gasket 9 and the excess metal which is distorted during the sealing operation is formed 85 into a double walled inclined ring or shelf 18 which incloses but a very small amount of the gasket. The upper portion of the gasket is supported by the annular groove formed as at 19. It will be noted that this 90 type of closure provides a relatively large amount of compressed gasket of substantially uniform cross-section, so that a larger range from standard sizes is allowed so far as the glass structure is concerned. Furthermore, in this type of device a larger amount of the gasket is permitted to flow 95 from between the forming dies so that the final pressures are more nearly radial pressures, consequently requiring less power to 100 close the sealing chucks, thereby utilizing less power in performing the sealing operation. Since the deformation of the metal during sealing operation is substantially slight, with the exception of the fold which 105 takes place at the corner between the surfaces 5 and 6 to form the double walled ring 18, it will be evident that the lacquer on the surfaces will not be destroyed.

Heretofore in the art of closures of this 110

character, and particularly where such closures are used in sealing packages under a vacuum, it has been customary to puncture the cover to relieve the vacuum and then force the sealed bead over the top of the glass container, thereby unsealing the package. Such procedure is disadvantageous for various reasons, two of which are that the puncturing of the closure renders the closure substantially unfit for use as a temporary cover where the contents of the package are not entirely used up at once; and where a secure seal is effected against the side wall, the mechanical retaining power of the seal is so great that it is difficult to force the bead over the edge of the glass container even after the vacuum within the container has been destroyed. Because of the type of seal formed by the construction herein previously described, a portion of the gasket may be substantially released by bending up, by pounding or otherwise, a portion of the annular ring 18, as shown in Figs. 4 and 5. In order to take advantage of this fact an opening 20 is provided in the annular skirt 17 which enables the gasket to be forced downwardly as by means of the thumb, or suitable tool, (Fig. 4) to comprise the loop 21. After the loop 21 is formed the entire gasket may be stretched and removed from between the annular skirt 17 and the side wall of the container 1. The forming of the loop 21 breaks the vacuum, where this closure is used in sealing packages under vacuum, so that when the gasket is removed the cover may be easily and without effort lifted from the top of the unsealed container.

Having thus described my invention what I claim is:—

- 40 1. A closure provided with an annular beading, a gasket having a portion thereof displaced laterally under compression against the side wall of the container, the beading having an annular ring comprising a portion of the metal folded upon itself with the sides thereof substantially parallel, and a skirt depending from said annular ring and supporting the major portion of the said gasket.
- 45 2. A closure provided with an annular beading and a gasket displaced laterally under compression forces and against the side wall of the container, said beading having its upper wall in the form of a concave groove with the lower wall substantially parallel thereto, and a skirt depending from said lower wall and supporting the major portion of the gasket.

3. A closure comprising a top portion, a depending side wall, an annular ring formed in said side wall and comprising a portion of metal folded upon itself, a depending skirt below said annular ring, a gasket held under compression between the side wall of the container and the said skirt.

4. A closure comprising a cover portion, a side wall including a skirt, a gasket adapted to be held under compression between the container and said skirt, and an annular ring formed from the excess metal displaced during the sealing operation, said annular ring being substantially devoid of portions of the gasket.

5. A closure comprising a cover portion adapted to fit over the mouth of a container, a gasket, a skirt adapted to support said gasket under compression against the side wall of the container, an angular ring adjacent said skirt portion and formed of the excess metal from the sealing operation, said ring being substantially devoid of gasket material.

6. A closure comprising a cover member adapted to fit over the mouth of a suitable container, the side wall of said cover comprising a skirt, a gasket adapted to be maintained under pressure between said skirt and the side wall of the container, and an annular ring adjacent said skirt and being formed entirely from excess metal resulting from the sealing operation.

7. A closure comprising a cover member adapted to fit over the mouth of a suitable container and having a depending side wall comprising a skirt, a suitable gasket adapted to be maintained under pressure between the wall of the container and said skirt, and an annular ring formed entirely of excess metal produced during the sealing operation and containing substantially no gasket material.

8. A closure comprising a cover adapted to fit over the mouth of a suitable container and having a depending side wall including a skirt, said skirt being adapted to maintain a suitable gasket under pressure against the side wall of the container, said skirt being provided with a recess in the lower edge thereof, an annular ring above said skirt and inclined thereto, said annular ring being formed of excess metal developed during the sealing operation, the parts being constructed and arranged to enable the gasket to be removed when the annular ring is bent inwardly adjacent the specified recess.

HARRY E. TOWNSEND.
